STOP MOTION CONTROL FOR JACQUARD LOOMS

Lester Clarence Brady, Burlington, N. C., assignor of twenty-four and one-half per cent to George Washington Morris and twenty-four and one-half per cent to Shirley Webster

Application July 27, 1933, Serial No. 682,483

1 Claim. (Cl. 139—336)

This invention relates to a device designed for use in controlling stop motion mechanisms of the electrical type, used in connection with Jacquard looms.

5 The primary object of the invention is to provide means whereby the lingoos or weights of the jacquard mechanism, will operate to complete a circuit to the stop motion mechanism, when the lingoos drop, due to the fouling of the needles of the loom, breaking of the neck cords or other portions of the coupling or harness, stopping the loom, and thereby eliminating flaws in the cloth or design of the woven fabric.

10 Another object of the invention is to provide a device of this character which may be readily and easily installed for use with the usual Jacquard loom without the necessity of making alterations in the jacquard construction, to install the device.

15 20 With the foregoing and other objects in view, which will appear as the description proceeds, the invention resides in the combination and arrangement of parts and in the details of construction hereinafter described and claimed, it being understood that changes in the precise embodiment of the invention herein disclosed, may 25 be made within the scope of what is claimed, without departing from the spirit of the invention.

20 Referring to the drawings:

Figure 1 is an elevational view disclosing a device constructed in accordance with the invention, as mounted under a Jacquard loom mechanism.

25 Figure 2 is a plan view of the device.

Figure 3 is a vertical sectional view through the device, illustrating the lingoos in their normal operative positions.

30 Figure 4 is a view illustrating the usual Jacquard harness or coupling.

Referring to the drawings in detail, the frame of a Jacquard loom is indicated generally by the reference character 5, and the reference character 6 designates the usual lingoos or weights, 40 forming a part of a jacquard structure.

The device forming the subject matter of the present invention, includes vertical supporting rods 7, that rise from the bases 8, the bases being bolted to the surface or floor on which the 45 jacquard mechanism is supported, by means of the bolts 9.

The device also includes a box-like body portion indicated generally by the reference character 10, the same being provided with bearing members 11, that extend from the ends of the

body portion, the bearing members being designed to accommodate the vertical supporting rods 7, as clearly shown by the drawings.

Thus it will be seen that due to this construction, the box-like body portion 10 is mounted on the supporting rods 7, for vertical adjustment, so that the contact plate of the body portion, to be hereinafter more fully described, may be adjusted with respect to the lingoos 6, with which the plate cooperates, in accomplishing the purpose of the invention.

Set screws 12 are provided and extended through the bearing members, the set screws contacting with the rods 7, to hold the body portion 10, in its positions of adjustment.

15 The bottom of the body portion 10, is in the form of a plate 13, which has connection with the body portion, through the hinges 14, secured to the bottom, at one end thereof, the opposite end of the bottom being supplied with a latch member 15, whereby the bottom member may be normally held in its active position, however it will be seen that due to this construction, the bottom member may be swung downwardly, to permit of access to the lower ends of the lingoos 25 6, for adjustment or repair.

20 Secured to the bottom 13, and insulated therefrom, is a copper plate 16, which is of a size to completely cover the upper surface of the bottom 13, there being provided a post 17 that 30 extends through the bottom member and contacts with the plate 16.

Connected with the post 17, is a wire 18 that is in circuit with a suitable source of electricity, and which is also in circuit with the usual electrically controlled jacquard stop motion mechanism not shown.

35 The upper side of the body portion is covered with a strip of wire mesh material indicated at 19, the wire mesh material being held in position on the body portion, by means of the frame 20.

40 A binding post 21 extends through the frame and has connection with the wire 22 which wire is also connected with the jacquard stop motion mechanism not shown, providing the return circuit for the stop control mechanism.

45 The binding post 21 is in circuit with the wire mesh material 19, and the body portion is adjusted so that the lower ends of the lingoos 50 normally lie within the mesh of the wire mesh material, the lower extremities of the lingoos being normally spaced from the copper plate 16, as clearly shown by Figure 1 of the drawings.

55 These lingoos 6 are supported by the usual

couplings or harness and include bottom loops or hangers 23, to which the eyes 24 are connected, the eyes 24 being supported by the top loops or mid pieces 25 of the couplings.

- 5 These top loops or midpieces have connection with the neck cords 26, that in turn have connection with the jacquard hooks 27 that cooperate with the needles 28, the operation of the hooks being controlled by the movements of the griffs 29, over which the upper ends of the hooks fall, during the operation of the jacquard.

10 As is well known by persons skilled in the operation of jacquards, the operation of these needles 28 is controlled by the usual cards 30, that move 15 over the cylinder 31, the needles being urged towards the cylinder 31, by means of spring members contained in the spring box 32, through which the opposite ends of the needles extend.

15 In the operation of the device, assuming that 20 a break should occur in any portion of the coupling or harness, the lingo connected with the broken coupling or harness, will drop, the lower end thereof contacting with the plate 16, completing the circuit to the stop motion mechanism 25 not shown, through the wire mesh material 19, plate 16, and wires 18 and 22.

20 The jacquard mechanism is immediately stopped, and the operator may now repair the broken coupling or harness, preventing an imperfect weave known to the trade as seconds, and 30 which result in great loss to the producer.

In the event that for some reason, a needle 28

would not be forced through its opening of the card 30, and would only extend a portion of the distance within the opening, the hook 27 associated with this needle, would not operate, resulting in the dropping of the harness or coupling connected with the hook, so that the lingo associated therewith falls into engagement with the plate 16, completing the circuit to the stop motion mechanism, as previously described.

5 In view of the foregoing description, it is believed that a further detail description as to the 10 operation of the device is unnecessary.

Having thus described the invention what is claimed is:

15 The combination with the lingoes and electric stop motion mechanism of a jacquard, of an electric stop motion controlling device, comprising a box-like body portion, a contact plate covering the inner surface of the bottom of the body portion, a contact member constructed of wire mesh 20 material presenting square openings, held on the body portion in space relation with the contact plate, a frame secured over the second mentioned contact member securing the second mentioned contact member in position, the lingoes of the 25 stop motion mechanism extending into the square openings of the wire mesh contact member, filling the openings, and electric wires connected with the contact plate and contact member, whereby an electric circuit is completed when the 30 lingoes drop and engage the contact plate.

LESTER CLARENCE BRADY.
